UNITED STATES PATENT OFFICE.

ARTHUR JAMES THURLEY, OF LONDON, ENGLAND.

ADJUSTABLE SINGLE-LEVER PIPE AND NUT WRENCH WITH RATCHETLIKE CONTROL.

Application filed March 13, 1924, Serial No. 698,992, and in Great Britain April 26, 1923.

This invention relates to nut and pipe wrenches of the type wherein the opposing toothed or serrated jaws of the wrench are formed upon two lever members pivoted together. In such tools as hitherto made both levers are generally extended to form the handle, and it is necessary for the user to grip the handles in order to maintain the jaws of the wrench in gripping position. It is the object of the present invention to provide an improved construction of wrench wherein the user may release his grip on the handle without necessarily removing the wrench from the nut or pipe which is being gripped, and whereby a series of grips may be taken in a ratchet like manner.

The improved wrench comprises the combination of a lever carrying one jaw and forming a lever handle, a second lever carrying the other jaw and pivotally and preferably adjustably mounted on the lever handle, a spring lever pressing the two levers together in the gripping direction so that the lever handle may be released without necessarily removing the wrench, and by moving back the handle the spring lever will permit the jaws to spring back in the manner of a ratchet brace to a new gripping position.

The second lever which may carry the outer or hooked member of the jaw may be adjusted upon the lever handle by means of a rack consisting of a series of notches adapted to engage with a pin on the lever handle, the said rack and pin being pressed into engagement by the spring lever which engages the back of the said second lever.

In the accompanying drawings, Fig. 1 is a face view, and Fig. 2 a side view showing one form of the improved wrench.

Fig. 3 shows a modified method of fitting the jaw to the lever handle of the wrench.

In the construction illustrated *a* is a lever handle having one member *b* of the jaw fitted at its outer end, *c* is the second lever hooked at its outer end and carrying the other or outer jaw *d*, this second lever is adapted to slide in a slot *e* in the lever handle *a* and is provided on its outer edge with a rack *f* consisting of notches adapted to engage with a pivotal pin *g* riveted in the lever handle so as to extend across the slot *e*. *h* is a spring lever pivoted in the slot of the lever handle *a* and provided with a long arm *h'* and a short arm *h''*, the long arm *h'*

being adapted to lie along and press upon the back edge of the second lever *c* whilst the shorter arm *h''* is pressed outward by a spring *i* and is also shaped to form a finger grip whereby the pressure of the long arm *h'* on the second lever *c* may be released to permit the said lever *c* to slide in the slot *e* and the rack *f* to be adjusted to vary the dimensions of the wrench jaw as required. 60 65

A small stud *j* may be fitted to prevent the second jaw from being drawn too far out of the slot *e*.

The levers are shown as fitted with removable steel jaws *b* and *d* fastened in position by studs and pins, and Fig. 3 shows a modified construction adapted to release the stress upon the securing studs and pins and wherein the removable jaw *b* is formed with a ledge *b'* at its inner and lower edge fitted into a corresponding recess in the end of the lever handle *a*. 70 75

In use, the jaws of the wrench are adjusted by means of the rack *f* and pin *g* for which purpose the pressure of the spring lever *h* is released by pressing upon its small arm *h''*. 80

The pipe or nut is gripped in the jaws in the usual manner. The long arm *h'* of the spring lever *h* presses against the back of the second lever *c* in the gripping direction so that the user of the wrench may release his grip without necessarily removing the wrench from the nut or pipe for the reason that the pressure of the spring lever *h* will impart sufficient gripping pressure to maintain the wrench in position, and further, by swinging back the handle lever *a* the jaws will open against the pressure of the spring lever and automatically take a new gripping position so that the operator may proceed to take a series of grips by merely moving the lever handle backwards and forwards. 85 90 95

What I claim as my invention and desire to secure by Letters Patent is:— 100

1. A wrench comprising a slotted handle, a pin projecting across the slot, an inner jaw carried by the slotted handle, an outer cooperating jaw, a shank carrying said outer jaw and having notches therein adapted to selectively engage with the pin in said slotted handle, and a double armed lever carried pivotally by said handle, but extending for its major portion wholly aside from the slot and plane of the handle, said lever having an elongated arm extending in contact with one edge of said shank through- 105 110

out an extensive area thereof, said lever having a short arm situated close to the handle and substantially parallel therewith to admit of being depressed by the hand in the act of holding the handle, and yieldable means for urging said short arm away from the handle and the long arm against said shank.

2. A wrench comprising a slotted handle having a pin extending thereacross, an inner jaw carried by said handle, a slotted shank extending slidably and laterally through said slotted handle and adapted to engage selectively with said pin, an outer jaw carried by said shank, a double armed lever composed of a long and short arm curved reversely, said long arm having a

flat edge adjacent the shank and adapted to lie in contact throughout said flat edge with said shank, said long arm extending outwardly beyond the pin, the short arm extending substantially parallel with said handle and arranged close thereto, a coil spring carried by said handle and engaging the inner side of said short arm to urge the same outwardly, said double armed lever having an intermediate extension for entering said slot while the remaining two arms of said lever lie wholly without the slot of the handle, and a pivot in the slot of the handle for engaging the extension of the double arm. 25 30
